UNITED STATES PATENT OFFICE.

HIRAM N. WILSON, OF OMAHA, NEBRASKA, ASSIGNOR TO HENRY M. WILSON, OF OMAHA, NEBRASKA.

SAFETY TIRE VALVE.

Application filed April 12, 1923. Serial No. 631,537.

To all whom it may concern:

Be it known that I, HIRAM N. WILSON, a citizen of the United States, residing at Omaha, in the county of Douglas and State 5 of Nebraska, have invented certain new and useful Improvements in Safety Tire Valves; and I do hereby declare the following to be a full, clear, and exact description of the invention, such as will enable others skilled in 10 the art to which it appertains to make and use the same.

The present invention relates to safety or high pressure escape valves for pneumatic tires, and aims to provide a valve construction of novel and improved formation and structure for attachment to the usual valve stem of a pneumatic tire, and adjustable to permit of the escape of air above a predetermined pressure, should the pressure of 20 the air increase due to an increase in temperature, or the like, thereby avoiding the excessive pressure on the tire casing and possible blow-outs.

Another object is the provision of such a 25 device comprising a novel combination and arrangement of parts, and which is simple and inexpensive in construction, as well as practical and efficient in use.

With the foregoing and other objects in 30 view, which will be apparent as the description proceeds, the invention resides in the construction and arrangement of parts hereinafter described and claimed, it being understood that changes can be made within 35 the scope of what is claimed, without departing from the spirit of the invention.

The invention is illustrated in the accompanying drawing, wherein—

Fig. 1 is a side elevation of the device applied to the valve stem, with the dust cap in 40 section, some of the parts being turned at a small angle with reference to the showing in Fig. 2.

Fig. 2 is a longitudinal section of the device, portions being shown in elevation.

Fig. 3 is a fragmentary elevation showing the rod turned to releasing position.

The device comprises a barrel or tubular casing 7 having a threaded socket 8 at one 50 end to screw onto the tip 9 of an ordinary valve stem 10 of a pneumatic tire, and said barrel or casing has a threaded socket 11 at its other end into which a bushing or plug 12 is threaded. The plug 12 has a longitudinal central bore 13 through which a rod 55

14 extends for sliding and turning movements, and said rod extends axially within the barrel 7 and through a reduced or contracted portion 15 within the barrel near the socket 8. The end of the rod 14 which projects into the socket is adapted to abut the valve member 16 within the stem 10, for pushing the usual valve open.

The barrel 7 has an inner cylindrical bore 17 between the reduced portion 15 and socket 11, with escape apertures or ports 18, and a valve member 19 of leather, rubber or other suitable compressible material is fitted on the rod 14 within the bore 17, to have an air tight fit with said rod and the barrel, and to slide within the barrel like a piston. The valve member 19 is disposed between a pair of metal or similar washers 20 and 21, and a stop pin 22 is carried by the rod 14 for the contact of the washer 21, to limit the movement of the valve member toward that end of the rod 14 which abuts against the valve member 16. A coiled expansion spring 23 surrounds the rod 14 and is confined between the washer 20 and plug 12, said plug 80 having a recess 24 receiving the spring and forming a shoulder 25 against which the spring bears. The valve member 19 and washers 20 and 21 are slidable on the rod 14, in the barrel 7, and said rod is also slidable 85 through said valve member and washers when slid in the plug 12.

The outer end of the plug 12 has a diametrical groove or notch 27 to receive a T-head 26 on the outer end of the rod 24, and cams 28 on which the head 26 can ride when said head and rod are turned at an angle with the groove 27. The cams 28 have notches 29 into which the head 26 can seat, when the head is turned to pull the rod 14 95 outwardly, as seen in Fig. 3.

The plug 12 is adjusted within the barrel or casing 7 to apply the desired tension to the spring 23 to resist the outward movement of the valve member 19, which is located inwardly of the ports 18 as seen in Fig. 2. When the barrel 7 is threaded on the stem 10, the rod 14 will abut against and move the valve member 16, so that the valve member in the stem 10 is opened, for the flow of air 105 outwardly into the barrel against the valve member 19. The spring 23 will resist the outward movement of the valve member or piston 19 by the air pressure from within the tire, but when the pressure increases above 110

a predetermined amount, for which the plug 12 has been adjusted, the valve member 19 is forced outwardly sufficiently so that the air can escape through the ports 18. The 5 outward movement of the rod 14 is limited, by the dust cap 30, to prevent the valve member 16 from closing when the valve member 19 is forced outwardly. Moreover, the valve member 19 reaches the ports 18, and permits the escape of air, before the rod 14 can move sufficiently to permit the valve member 10 16 to close, the pin 22 contacting with the valve member 19 and preventing the rod 14 from moving further than the valve member 15 19. Consequently, although the valve member 19 can move outwardly for the escape of air through the ports 18, the same movement of the rod 14 will not enable the valve member 16 to close, even though the outward 20 movement of the rod 14 is not limited by the cap 30. When the pressure is relieved, the spring 23 will return the valve member 19 to prevent further escape of air. This will 25 avoid excessive pressure, and possible blowing-out of the tire. When the air pressure is sufficiently low, or when the plug 12 is removed from the barrel 7, the valve member 19 can seat against the pin or stop 17 under the tension of the spring 23, thereby preventing 30 the separation of the parts 12, 14, 19 and 23. The dust cap 30 which is threaded on the stem 10 can be screwed into place to bring its outer closed end against the head 26 of the rod 14 to prevent the outward 35 movement of said rod with the valve member 19, which, if it occurred, would be apt to permit the valve member 16 in the stem 10 to close and prevent the escape of the excessive pressure. When it is desired to 40 render the device inoperative, and to permit the valve member 16 to remain closed, the head 26 of the rod 14 is turned on the cams 28, thereby drawing the rod outwardly to release the valve member 16 and the head 45 26 will seat in the notches 29.

Having thus described the invention, what is claimed as new is:—

1. A safety tire valve including a barrel for attachment to a valve stem of a tire, a rod slidably mounted in said barrel for holding open a valve member in said stem, said barrel having an air escape port, a valve member in the barrel movable outwardly for the escape of air through said port, spring 50 means for resisting the outward movement of the secondnamed valve member and for moving said secondnamed valve member inwardly, a stop carried by said rod for the contact of the secondnamed valve member 55 when moved inwardly by said spring means so that the spring means yieldingly moves said rod inwardly to open the firstnamed 60

valve member, and means for holding said rod in outwardly retracted position when slid outwardly away from the firstnamed 65 valve member with the secondnamed valve member moved outwardly by said stop against said spring means.

2. A safety tire valve comprising a barrel for attachment to a barrel stem of a pneumatic tire, a plug adjustably connected to the outer end of said barrel, a rod slidable in said plug and movable inwardly for holding open a valve member in said stem, the barrel having an air escape port, a valve member 70 movable outwardly in the barrel to permit the escape of air through said port, spring means between said plug and secondnamed valve member to resist the outward movement of the secondnamed valve member and to move said valve member inwardly, and a stop carried by said rod for limiting the movement of the secondnamed valve member away from the plug so that the spring means yielding moves said rod inwardly to open the firstnamed valve member, said rod and plug having cooperable portions to limit the inward movement of said rod and to hold said rod in outwardly retracted position when slid outwardly away from the firstnamed 75 valve member with the secondnamed valve member moved outwardly by the stop against said spring means.

3. A safety tire valve comprising a barrel having means at one end for attachment to 95 a valve stem, and having an escape port, a plug adjustably connected to the other end of the barrel, a rod extending slidably and rotatably through said plug for opening a valve member in said stem, a valve member 100 slidable in the barrel on said rod to said port for the escape of air, a stop on the rod for limiting the movement of the lastnamed valve member away from the plug, spring means between the lastnamed valve member 105 and plug for resisting the movement of said valve member to said port and for yieldingly moving said rod in the direction to open the firstnamed valve member when the lastnamed valve member engages said stop, the 110 outer end of said rod having a portion to bear against the outer end of said plug, and the outer end of the plug having a cam for the engagement of said portion of the rod when turned, to pull the rod outwardly and 115 release the firstnamed valve member.

In testimony whereof I have signed my name to this specification in the presence of two subscribing witnesses.
